CLAIM

The ornamental design for a bottle, as shown and described.

DESCRIPTION

FIG. 1 is a front elevational view of a bottle embodying my new design, the rear elevational view being the same in appearance;

FIG. 2 is a right side elevational view thereof, the left side elevational view being the same in appearance;

FIG. 3 is a top plan view thereof; and

FIG. 4 is a bottom plan view thereof.

The broken line showing of a bottle cap in FIGS. 1 and 2 is for illustrative purposes only and does not form part of the claimed design.
